IGNITION CUT-OUT

Joseph J. Jwanouskos, Jr., St. Paul, Gustav C. Lundgren, Minneapolis, and James D. Swan, Jr., North St. Paul, Minn., assignors to Joseph J. Jwanouskos, Sr., St. Paul, Minn.

Application January 13, 1936, Serial No. 58,882

16 Claims. (Cl. 123—146.5)

Our invention relates to ignition cut outs for motor vehicles and particularly to cut outs for stopping the motor of a vehicle after the motor has been idling for a predetermined length of time.

Devices of such nature heretofore employed have been extremely complicated utilizing parts controlled by centrifugal force, or by thermostatic means. Many of such devices require reconstruction of the motor vehicle and others cannot be installed on existing vehicles.

An object of the invention resides in providing a cut out which will be simple in construction and positive in action and which is not controlled by centrifugal force or thermostatic action.

Another object of the invention resides in providing a cut out which can be easily and quickly installed on existing motor vehicles.

A still further object of the invention resides in providing a cut out utilizing clockwork for procuring the timing thereof.

An object of the invention resides in providing a cut out in which the clockwork is actuated by a reciprocable member connected to the gear shift lever of the motor vehicle.

Another object of the invention resides in providing a cut out utilizing a spring actuated clockwork and in providing means for winding said spring upon the shifting of the gear shift lever from neutral position to any of its driving positions.

A still further object of the invention resides in providing a mechanism by means of which the clockwork is held from movement when the gear shift lever is in driving positions and is released as soon as the gear shift lever is moved into neutral position.

Another object of the invention resides in providing compensating means for permitting of installing the invention on motor vehicles in which the gear shift levers move throughout arcs of different angularity.

A feature of the invention resides in providing an actuating lever for actuating the clockwork and means operable by said reciprocable member for procuring movement of the actuating lever in the same direction upon movement of said reciprocable member in either direction.

Another object of the invention resides in providing a case and in mounting said clockwork and the other parts associated therewith within said case.

A still further object of the invention resides in providing a tubular housing connected at one

end to said case and at its other end to a support positioned adjacent the gear shift lever.

A feature of the invention resides in providing means for connecting said housing at the support for universal movement to permit of the shifting of the gear shift lever laterally.

Another object of the invention resides in providing resilient means either in the connections between the reciprocable member and the parts connected therewith or between the housing and the attaching means therefor or both.

Other objects of the invention reside in the novel combination and arrangement of parts and in the details of construction hereinafter illustrated and/or described.

15

In the drawings:

Fig. 1 is a perspective view of a motor vehicle including the gear shift lever and illustrating the application of an embodiment of my invention thereto.

20

Fig. 2 is a plan sectional view taken on line 2—2 of Fig. 1 and drawn to a larger scale.

20

Fig. 3 is an elevational view of the case of the invention with the closure therefor removed and illustrating the parts in one position.

25

Fig. 4 is a view similar to Fig. 3 showing the parts in altered position.

Fig. 5 is an inverted plan sectional view taken on line 5—5 of Fig. 3.

30

Fig. 6 is an elevational view of the clockwork of the invention detached from the case.

30

Fig. 7 is a view similar to Fig. 6 showing the parts in altered position.

35

Fig. 8 is a fragmentary cross sectional view taken on line 8—8 of Fig. 6.

35

Fig. 9 is a view similar to Fig. 3 illustrating a modification of our invention.

For the purpose of illustrating the application of the invention, a portion of a motor vehicle indicated in its entirety by the reference numeral 40 A has been shown in Fig. 1. Inasmuch as the invention is concerned only with certain parts of the vehicle, the parts not associated therewith will not be described. The vehicle A includes a dash 10, and a floor 11 having an inclined portion 12 extending up to the dash 10. The vehicle further includes a gear shift lever 13 which is mounted in a mounting 14 secured to the chassis of the vehicle and extending upwardly through the floor 11. Gear shift lever 13 includes a vertical portion 15 issuing upwardly from the mounting 14 and an inclined portion 16 bent with respect to the portion 15. The portion 15 extends down into the mounting 14 and has attached to it a cover 17 permitting the lever 13 to

40

45

50

55

to operate in the usual manner. In the construction shown, lever 13 is adapted to swing forwardly and rearwardly and also to be shifted laterally so that the same may be moved from 5 its neutral position to either of four driving positions, one of said driving positions procuring reverse movement of the vehicle.

Our invention proper comprises a clockwork forming a timing mechanism indicated at its 10 entirely by the reference numeral 18 which is mounted in a case 19 secured to the dash 10.

A tubular housing 21 is attached to the case 19 and is further attached to a support 22 mounted on the inclined portion 12 of floor 11. Within 15 the housing 21 is disposed a flexible cable 23 which is connected to the gear shift lever 13 and which operates the timing mechanism 18, as will be subsequently more fully described. The various parts will now be described in detail.

20 The case 19 may be constructed of sheet metal and in such case comprises a back 24, upper and lower walls 25 and 26 and side walls 27 and 28, being open at the forward portion of the same. This case is closed by means of a cover 31 having 25 flanges 32 extending outwardly therefrom and about the walls 25, 26, 27 and 28 of the case when the cover is applied to the case. The case 19 is attached to the dash 10 by means of screws or bolts, not shown, which extend through 30 openings 33 in the back 24 of the case and are screwed into the dash 10. The closure 31 is attached to the case proper by means of screws 34 which extend through the flanges 32 and are threaded into the various walls of the case.

35 Support 22 consists of a bracket indicated by the reference numeral 35 which is formed with an upstanding leg 36 and a flange 37 adapted to rest upon the inclined portion 12 of floor 11. Bracket 35 is secured to the floor by means of 40 screws 38 which extend through the flange 37 and are screwed into the portion 12 of the floor. Support 22 is situated directly in front of gear shift lever 13, being disposed a short distance ahead of the same.

45 The tubular housing 21 is preferably flexible and is mounted at one end in a mounting 41 attached to the case 19 and at its other end in a mounting 42 associated with the support 22. Mounting 41 consists of a short tube 43 which is reduced in diameter at one end as indicated at 44 and threaded to receive a nut 45. The reduced end 44 of the tube 43 passes through an opening 46 in the wall 28 of case 19 and the shoulder formed through said reduced portion 50 abuts against this wall. A washer 47 disposed upon portion 44 adjacent the wall 28 and the nut 45 screwed on said portion, serves to urge the washer against said wall and to attach the tube 43 to case 19. Housing 21 is received in the 55 end of the bore 48 of the tube 43 and secured thereto. The bore 48 extends throughout the entire length of tube 43 and slidably supports a rod 51 attached to the end of the cable 23.

60 The other end of the housing 21 is supported in the mounting 42 in the following manner: In the leg 36 of bracket 35 is a hole 52 which is at the medial plane of the lever 13. This hole is countersunk on both sides, as indicated in Fig. 2. A sleeve 53 extends through this hole and is 65 provided at one end with a head 54 and is threaded at its other end 55 to receive a nut 56. Upon the sleeve 53 are mounted two conical shaped collars 57 and 58 which fit into the sockets formed through the countersinking of the 70 hole 52. A compression coil spring 61 encircling

the sleeve 53 is seated at one end against the nut 56 and at its other end against the collar 57. A similar compression coil spring 62 which also encircles said sleeve is seated at one end against the head 54 and at its other end against the collar 58. Housing 21 extends into the bore 63 of sleeve 53 and is attached thereto by soldering or otherwise. The bore 63 slidably supports a rod 64 to which the other end of the cable 23 is attached. It will readily become apparent 10 that the cable 23 by means of the mounting 42 may have universal movement to permit of the shifting of the gear shift lever 13 and at the same time may move longitudinally through the yielding of the springs 61 and 62 for a purpose 15 to be subsequently more fully described.

Cable 23 is connected to the gear shift lever 13 in the following manner: A clamp 65 is utilized which consists of two members 66 and 67 constructed preferably of strap iron and bent 20 to provide socketed portions 68 with ears 71 and 72 extending outwardly therefrom. The socketed portions 68 fit about the portions 15 of the gear shift lever 13 and are held in engagement therewith by means of bolts 73 and 74 which extend through the ears 71 and 72. The forward portions of ears 72 are spaced and are drilled to receive another bolt 75. A connecting rod 76 is employed which is constructed with a tongue 77 adapted to extend between the ears 72. Bolt 75 30 also passes through this tongue and forms a pivot for the rod 76. Rod 76 is internally threaded as indicated at 78 and the end of the rod 64 previously referred to, is threaded at 81 to screw into the threads 78. By means of this construction the cable 23 is reciprocated when the gear shift lever 13 is operated and the rod 51 secured at the other end of said cable moved toward and from the wall 27 of the case 19.

The clockwork 18 is best shown in Figs. 6, 7 and 8 and comprises two bearing plates 82 and 83 which are held in spaced relation by means of studs 84. The clockwork further comprises a gear train 85 of usual construction which includes the usual escapement and associated parts 45 which have not been shown. The gear train 85 also includes a main gear 86 which meshes with a pinion 87. Attached to plate 82 is a stub shaft 98. An arbor 91 is journaled at one end in the bearing plate 83 and at its other end in the stub shaft 98. This arbor has secured to it a hub 88 which is formed with a shoulder 79. A washer 80 butts against this shoulder and gear 86 is disposed adjacent said washer. The gear 86 is engaged by a friction washer 89 which is riveted to the hub 88 and exerts pressure against said gear. Hub 88 has rigidly attached to it a segment 92 which is formed at one locality with a shoulder 93 and at another locality with a notch 94.

On the stub shaft 98 is formed a shoulder 90. Adjacent this shoulder is a washer 99 similar to washer 80. An adjusting lever 105 to be subsequently more fully described encircles the stub shaft 98 and is disposed adjacent washer 99. 65 This lever is frictionally engaged by a friction washer 100 similar to washer 89, which is secured to said stub shaft and urges the segment against washer 99.

For providing power to operate the gear train 70 85, a spiral spring 95 is employed which is rigidly attached at one end to the stub shaft 98 and at its other end to a lug 96 secured to a lever 97. Lever 97 is pivoted on the stub shaft 98 which is secured to the plate 82 and is disposed between 75

said spring and washer 99 next to plate 82. The lever 97 has mounted on it a post 102 to which is pivoted a pawl 101. Pawl 101 is provided with an abutment 103 which is adapted to engage the shoulder 93 of segment 92 and to rotate the same. Pawl 101 is further provided with a hook 104 which is adapted to engage into the notch 94 and to procure movement of the segment 92 in the opposite direction. Hook 104 of pawl 101 is urged into engagement with notch 94 by means of a spiral spring 110 which encircles post 102 and has its ends secured to said pawl and to the lever 97. When the lever 97 is moved from its position shown in Fig. 6 in which the spring 95 is unwound toward its position shown in Fig. 7, spring 95 is tensioned. At the same time the segment 92 is shifted as illustrated. Upon releasing of the pressure against lever 97 force is applied to segment 92 to cause the gears to rotate and the timing mechanism is set into operation.

For the purpose of controlling the length of time that the clockwork will operate, the adjusting lever 105 is used. This lever as previously described is pivoted upon the stub shaft 98 and is frictionally held thereon by means of the spring 100, said lever remaining in any of its adjusted positions. Lever 105 has formed on it a cam 106 which is adapted to engage a lug 107 on pawl 101. The lever 105 once the same has been set remains stationary and as the lever 97 and segment 92 rotate lug 107 approaches cam 106. When the said lug reaches the cam it climbs the spiral cam surface thereof and hook 104 is disengaged from the notch 94, freeing lever 97 from segment 92. As soon as this occurs power is removed from the gear 86, the gear train stops and the lever 97 moves back to its original position as shown in Fig. 6. In Fig. 6 of the drawings the lug 107 is shown as in engagement with the cam 106 and the hook 104 is freed from the notch 94. By regulating the position of lever 105 any degree of timing can be procured.

The clockwork 18 operates an electric switch indicated in its entirety by the reference numeral 108. This switch includes a stationary switch leaf 109 which is disposed between insulating blocks 110 secured between the plates 82 and 83 of the clockwork. To hold the said plates in position, bolts 111 extend through the same and are insulated from the leaf 109. A stop 112 which forms no portion of the electrical circuit is also included between the blocks of insulating material 110 and limits the movement of the movable switch leaf away from the stationary switch leaf. The movable switch leaf is designated by the reference numeral 113 and is attached to an insulating support 116. This support is pivoted by means of fulcrums 117 which are engaged within sockets 118 in the plates 82 and 83. The switch leaf 113 is movable between the stop 112, and switch leaf 109. For urging said switch leaf into engagement with the stop 112, a spiral spring 119 is employed which is wrapped about one of the studs 84 and is anchored at one end to another stud 122 which is secured to plate 83. This spring is secured at its other end to the insulated member 116 as best shown in Fig. 6.

The switch 108 is operated as follows: Member 116 has attached to it a lug 123 which is adapted to engage a cam 124 on the lever 97. The cam 124 is provided with a hump 125 which forces the lug 123 outwardly against the action of the spring 119, bringing the switch leaf 113 into contact with switch leaf 109. As the lever 97 travels through

the action of the spring 95, the lug 123 rides on the raised portion 126 of cam 124 and during such time maintains contact between the two switch leaves. When the said lug reaches the portion 125 of said cam it drops and breaks the circuit through the switch. It will thus be seen that when the lever 97 reaches normal position such as shown in Fig. 6, that the switch 108 is opened. The switch 108 is connected in the ignition circuit of the motor vehicle. When this switch is opened the motor is deprived of ignition current and immediately stops. Inasmuch as the installation of this switch is obvious, a wiring diagram illustrating the same has not been shown.

The clockwork 18 is mounted on the back 24 of case 19 by means of two machine screws 127 which extend through ears 128 on the plate 82 of the said clockwork. These machine screws pass through spacer sleeves 121 which rest upon the back 24 of case 19 and are screwed into said back, thereby holding the clockwork spaced therefrom.

For the purpose of operating the winding lever 97 an actuating lever 132 is employed. This lever is pivoted by means of a stud 133 secured to the back 24 and extends along said back beneath the clockwork 18. One end of lever 132 is constructed with a finger 134 turned upwardly therefrom which is adapted to engage lever 97. When the lever 132 is swung from its position shown in Fig. 3 to that shown in Fig. 4, the lever 97 is moved throughout its range of movement and winds the clock spring. Lever 132 is urged into its position shown in Fig. 3 by means of a tension coil spring 139 which is secured at one end to said lever and at its other end to a lug 140 attached to wall 26 of case 19.

For moving the actuating lever 132 an operating member 135 is employed. This member is constructed from sheet metal and is provided at the intermediate portion of the same with a slot 136. This lever slides along two headed studs 137 and 138 which fit snugly within the slot 136. The heads thereof maintain the member 135 in close proximity to the back 24. Member 135 has issuing outwardly from it in opposite directions two arms 141 and 142 which are constructed with fingers 143 and 144 projecting outwardly therefrom. The fingers 143 and 144 are disposed the same distance from the center line of the slot 136 and are adapted to engage the lever 132 on opposite sides of the pivot 133 thereof. Pivot 133 extends along the center line of slot 136. It will thus become apparent that either of the fingers 143 or 144 will move the lever 132 the same distance and in the same direction when the member 135 is reciprocated in either direction.

The operating member 135 is operated by means of the rod 51 which extends through a leg 145 bent upwardly from said operating member. Washers 146 and 147 encircle the rod 51 on opposite sides of the leg 145 and are spaced therefrom. These washers are held in position by means of cotter pins 148 which extend through said rod. A compression coil spring 151 encircles rod 51 and is disposed between the leg 145 and washer 146. A similar compression coil spring 152 encircles said rod and is disposed between leg 145 and washer 147. By means of these springs a yielding connection is formed between the gear shift lever 13 and the clock mechanism whereby differences in movement of said gear shift lever into and out of any of its driving positions may be compensated for.

The operation of the invention is as follows:

Normally when gear shift lever 13 is in neutral position, switch 108 is open. Before attempting to start the vehicle, it is necessary to shift gear shift lever 13 into one of its driving positions and 5 to immediately shift the same back into neutral position. The driver then starts the vehicle in the usual manner. Where the timing mechanism is set for say three minutes, the driver has three minutes from the time that the gear shift lever 10 is first operated to get his motor started. If longer time is required, the driver can shift the lever 13 into one of its driving positions and disconnect the motor from the drive wheels by means of the clutch and in such case any required 15 length of time may be had for the purpose. Assume that the lever 13 was shifted into low driving position. This would reciprocate rod 64 and cable 23 connected therewith rearwardly and cause the rod 51 to be projected away from the 20 case. The position of rod 51 and the operating member 135 when in normal position is shown in Fig. 3. In such position the finger 143 is in position to engage lever 132 above the pivot 133. Movement of said rod 51 and operating member 25 28 as specified would cause finger 143 to force lever 134 into the position shown in Fig. 4. The position of operating member 135 would then be as indicated in full lines in Fig. 4. During the movement of lever 132 from its position shown 30 in Fig. 3 to that shown in Fig. 4, the winding lever 97 would be moved from its position shown in Fig. 6 to that shown in Fig. 7, in a manner to wind the spring 95. At the same time the abutment 103 would engage the shoulder 93 and slide 35 the segment 92 with respect to gear 86. The parts would then be in the position shown in Fig. 7. During movement of lever 97 from the position shown in Fig. 6 to that shown in Fig. 7, lug 123 is engaged by the hump 125 of cam 124 which 40 forces the switch leaf 113 outwardly bringing the same into engagement with switch leaf 109 and closing switch 108. As long as lever 97 is held in such position, the power from spring 95 is not transferred to the gear train 85 and switch 108 45 remains closed. As soon as the gear shift lever 13 is moved into neutral position, spring 139 returns lever 132 to its position shown in Fig. 3 and the pressure on the winding lever 97 is released. When this occurs said lever through the action 50 of spring 95 energizes the gear train 85 and the clockwork is set into motion. If the gear shift lever 13 within the time limit of the clockwork is shifted into another driving position, then lever 97 is moved back to its position shown in Fig. 7 55 and switch 108 remains closed. Assume that the lever is moved into its second speed position. Rod 64 would be moved forwardly and cable 23 moved in a direction toward case 19. This would move the operating member 135 until it reached 60 a position illustrated in dotted lines in Fig. 4, in which position the finger 144 engages the lever 132 upon the edge thereof below the pivot 133 of said lever. It will thus be seen that finger 144 moves the lever 132 in the same direction as finger 143 so that lever 132 is moved in the same direction whether the gear shift lever 13 is moved 65 forwardly or rearwardly from neutral position. As soon as the gear shift lever 13 is brought into neutral position, lever 97 moves toward the position shown in Fig. 6. If the gear shift lever remains in neutral position for a length of time greater than the time for which the clockwork is 70 set, lug 123 slides down the hump 125 of cam 124 and switch leaf 113 moves away from switch leaf 75 109 opening switch 108. This stops the motor

and the same can only be started upon repetition of the method of operation previously described.

In Fig. 9 we have shown a modification of the invention in which the case, clockwork and the cable and cable housing are exactly the same. 5 In place of the operating mechanism shown in Figs. 3 and 4 another operating mechanism is used which will now be described in detail. The remaining parts being the same, the same reference numerals have been used to designate the 10 corresponding parts.

In the form of the invention shown in Fig. 9 an actuating lever 161 is employed which is constructed with two arms 162 and 163. These arms extend angularly from one another and the said 15 lever is pivoted by means of a rivet 164 to the back 24 of case 19. The arm 162 of this lever is provided with a finger 165 extending outwardly therefrom which is similar to the finger 134 of lever 132. The arm 163 is provided at the end thereof 20 with a roller 166 which is pivoted thereto. Superimposing the arm 163 is an operating member 167 which takes the place of the operating member 135 of the other form of the invention. This operating member is similarly constructed with a slot 25 168 and is guided for reciprocating movement by means of two headed studs 171 and 172. These studs extend through the said slot 168 and through washers 173 which hold the operating member 167 spaced from the back 24 of the case 30 and are riveted to said case. Operating member 167 is constructed with a leg 174 similar to leg 145 of the other form of the invention and the rod 51 is attached to said leg in the same manner. The operating member 167 is constructed with 35 two cams 175 and 176 both of which function to throw the arm 162 of lever 161 in the position shown in dotted lines in Fig. 9. When the gear shift lever 13 is moved from neutral position to one of the driving positions, lever 161 is swung 40 in identically the same manner as lever 132 and the clockwork actuated as previously described.

The advantages of our invention are manifest. The invention may be installed on existing motor vehicles without difficulty and without requiring 45 special construction of the engine or transmission of the motor vehicle. The device operates independently of any of the rotating parts of the vehicle so that the use of centrifugally controlled devices and drives therefor may be eliminated. 50 With our invention any length of time within the limits of the device may be procured. A considerable saving in fuel and wear and tear on the motor of the engine will be possible. Our invention is extremely simple in construction and fool 55 proof in operation. The device can be constructed at a nominal cost. All of the working parts are enclosed within a single case which may be conveniently mounted on the dash under the cowl board, if desired, where the same is practically out of view. The invention automatically 60 compensates for varying movement of the gear shift lever.

Changes in the specific form of our invention, as herein disclosed, may be made within the scope 65 of what is claimed without departing from the spirit of our invention.

Having described our invention, what we claim as new and desire to protect by Letters Patent is:

1. In combination, a timing mechanism including clockwork, a switch actuated by said clockwork, an actuating lever adapted when moved in one direction to actuate said clockwork, an operating member movable in opposite directions, and means connected with said actuating lever and 70 75 75

said operating member for procuring movement of said actuating lever in the same direction upon movement of the operating member in either direction.

5 2. In combination, a timing mechanism including clockwork, a switch actuated by said clockwork, an actuating lever adapted when moved in one direction to actuate said clockwork, an operating member movable in opposite directions, and 10 10 companion engaging members connected with said operating member and engaging said actuating lever for procuring movement of said actuating lever in the same direction upon movement of the operating member in either direction.

15 3. In combination, a timing mechanism including clockwork, a switch actuated by said clockwork, an actuating lever adapted when moved in one direction to actuate said clockwork, an operating member movable in opposite directions, and 20 20 companion engaging members connected with said operating member and engaging said actuating lever, on opposite sides of the fulcrum thereof for procuring movement of said actuating lever in the same direction upon movement of the operating 25 member in either direction.

25 4. In combination, a timing mechanism including clockwork, a switch actuated by said clockwork, an actuating lever adapted when moved in one direction to actuate said clockwork, an operating member movable in opposite directions, and 30 30 companion cams connected with said operating member and engaging said actuating lever for procuring movement of said actuating lever in the same direction upon movement of the operating 35 member in either direction.

5 5. In combination, a case, a timing mechanism within the case including clockwork, an actuating lever within said case adapted when moved in one direction to actuate said clockwork, a reciprocable operating member extending into said case, said operating member being movable in opposite directions, and means connected with said actuating lever and said operating member and contained within said case, said means operating 40 to procure movement of said actuating lever in the same direction upon movement of the operating member in either direction.

45 6. In combination, an operating member movable in opposite directions, an actuating lever having a fulcrum intermediate its ends, companion engaging members connected with said operating member and engaging said actuating lever on opposite sides of the fulcrum thereof, and time controlled switch means operated by 50 said lever.

55 7. In a mechanism for operating a switch through movement of a member movable in opposite directions from an inoperative position to either of two operative positions, an operating 60 member moved by said first named member in opposite directions, an actuating lever having a fulcrum intermediate its ends and companion engaging members moved by said operating member and engaging said actuating lever on opposite sides of the fulcrum thereof and moving said lever in the same direction upon movement of the first named member in opposite directions to operate said switch.

70 8. In combination, a clockwork including a main spring, an actuating lever adapted when moved in one direction to wind said spring, a reciprocable operating member movable in opposite directions, and companion engaging members connected with said operating members and 75 engaging said actuating lever on opposite sides of

the fulcrum thereof for moving said actuating lever in a direction to procure winding of said spring upon movement of said operating member in either direction.

9. In combination, a clockwork including a 5 main spring, an actuating lever, a pivot therefor, said actuating lever being adapted when moved in one direction to wind said spring, a reciprocable operating member traveling in a line substantially intersecting the axis of said pivot, arms 10 on said operating member disposed on opposite sides of said pivot, and engaging members on said arms engaging said actuating lever on opposite sides thereof.

10. In combination, a clockwork including a 15 main spring, an actuating lever having a fulcrum intermediate its ends and adapted when moved in one direction to wind said spring, a reciprocable operating member movable in opposite directions, and companion engaging members connected with said operating member and engaging said actuating lever laterally of said operating member on opposite sides of said fulcrum and longitudinally of said operating member on opposite sides of said lever for moving said actuating 25 lever in a direction to procure winding of said spring upon movement of said operating member in either direction.

11. In combination, a clockwork including a main spring, an actuating lever having a fulcrum intermediate its ends and adapted when moved in one direction to wind said spring, a reciprocable operating member movable in opposite directions, and companion engaging members connected with said operating member and 30 adapted to contact with said actuating lever, laterally of said operating member on opposite sides of said fulcrum and longitudinally of said operating member on opposite sides of said lever, each of said engaging members leaving said lever 35 upon movement thereof by the other for moving said actuating lever in a direction to procure winding of said spring upon movement of said operating member in either direction.

12. In combination, a support, a clockwork 45 mounted on said support and including a main spring, an actuating lever having a fulcrum intermediate its ends and adapted when moved in one direction to wind said spring, a pivot for said actuating lever attached to said support, a reciprocable operating member traveling in a line substantially intersecting the axis of said pivot, said operating member being formed with a slot, means concentric with said pivot extending through said slot and guiding said actuating 50 member, and companion engaging members connected with said operating member and engaging said actuating lever on opposite sides of the fulcrum thereof for moving said actuating lever in a direction to procure winding of said spring 60 upon movement of said operating member in either direction.

13. In combination, a support, a clockwork mounted on said support and including a main spring, an actuating lever having a fulcrum 65 intermediate its ends and adapted when moved in one direction to wind said spring, said actuating member being spaced from said support, a pivot for said actuating member carried by said support, a reciprocable operating member disposed between said actuating member and support, arms formed on said operating member and extending laterally therefrom in opposite directions and disposed between said actuating member and fingers extending outwardly from said 70 75

arms and engaging said lever on opposite sides of said fulcrum for moving said actuating lever in a direction to procure winding of said spring upon movement of said operating member in either direction.

5 14. In combination, a clockwork including a main spring, an actuating lever having a pivot intermediate its ends and adapted when moved in one direction to wind said spring, a reciprocal operating member movable in opposite directions, and companion engaging members carried by said operating member and disposed at spaced intervals along said operating member and extending laterally to opposite sides of the 10 pivot of said actuating lever and engaging said actuating lever longitudinally of said operating member on opposite sides of said lever.

15 14. In combination with the gear shift lever of a motor vehicle and the ignition circuit of the 20 vehicle motor, a clock work including a winding lever, a switch operated by said clock work and included in said ignition circuit, winding means adapted to engage said lever for winding said clock work, transmission means connected to said 25 gear shift lever, means operated by said trans-

mission means when the gear shift lever is moved from neutral position forwardly for actuating said winding means, and means operated by said transmission means when the gear shift lever is moved from neutral position rearwardly for actuating said winding means.

16. In combination an operating member movable in opposite directions, an actuating lever having two arms, a cam follower carried by one of said arms, a cam carried by said operating member and having oppositely sloping surfaces meeting intermediate the ends of the cam and adapted to be engaged by said cam follower, said lever being adapted to be moved in the same direction upon movement of said operating member in opposite directions from the position of the cam when the meeting portions of the cam surfaces engage the cam follower and a clock work adapted to be wound by said lever upon movement of the operating member in opposite directions.
